METHOD OF AND APPARATUS FOR
EXCAVATING

Leo Ranney, Morro Bay, Calif.

Application December 20, 1933, Serial No. 703,193

24 Claims. (Cl. 262—6)

My invention relates to means for excavating earth material, and particularly to means for excavating appropriate material which usually is unconsolidated, although somewhat consolidated material can likewise be handled.

Some excavating work requires the use of casings, and in sinking casings to a considerable depth, say, to eighty or one hundred feet or more, the efficacy of the customary orange-peel or clam-shell bucket rapidly decreases. The time involved for a given job increases considerably; the hazard to workmen, especially if compressed air is utilized in the casing, is more serious; and the expense per foot of depth increases very rapidly. These difficulties are due to various causes. Among others, especially in subaqueous work, is the deleterious factor that much of the earth material is washed out of the bucket as the bucket is passing through the water in the casing, while the mere presence of water in the casing reduces considerably the possible speed of operation of the bucket. The bucket lines are prone to twist, and it is impossible to dig close against the sides of the casing. This latter factor is especially disadvantageous in the event the casing is non-circular. To overcome some of these difficulties, special excavating machines for the sinking of casings have been developed, but in every instance these machines not only are bulky and initially expensive but are very expensive to operate. They are therefore not practical unless there is a large number of casings to sink at one location, and, even so, they can be used only when conditions are favorable, for instance, in tough, heavy clay. They are not of value for use in running ground or quicksand and are of no use in instances where the material is likely to cave or heave up in the bottom of the hole. There is another alternative for the sinking of casings of not much more than three feet in diameter. This scheme utilizes a bailing bucket which is of substantially the same diameter as the inside of the casing in order to maintain the bailing or bucket upright while digging. Here, too, the presence of water in the casing considerably restricts the speed of operation, and the necessity for having a relatively large bailing limits the size of casing and, consequently, of the hole which can be dug. Again, anything but circular casings are out of the question for this method of operation.

It is therefore an object of my invention to provide an improved apparatus and method for excavating.

55 A further object of my invention is to pro-

vide a method and apparatus which overcome substantially all of the difficulties hereinabove enumerated.

An additional object of my invention is to provide a method and apparatus for sinking a casing of virtually any size through unconsolidated or somewhat consolidated material, without limitation with respect to depth and with considerably greater economy than with any method or apparatus heretofore known. 5

A further object of my invention is to provide an apparatus for excavating which is useful in connection with my method and which is initially inexpensive to construct.

The foregoing and other objects will appear 15 from the embodiment of the invention as set forth in the drawings, in which—

Figure 1 is a schematic view, portions being in cross-section and portions being in elevation, showing the apparatus of my invention as it appears in an excavating job in sinking a casing. 20

Figure 2 is a schematic view, portions being in cross-section and portions being in elevation, showing a modified form of my apparatus as it appears in an excavating job of a different character. 25

Figure 3 is, on the left half, a side elevation, and on the right half, a cross-section on a diametral plane, of a drill bit and associated mechanism constructed in accordance with my invention. 30

Figure 4 is a cross-section the plane of which is indicated by the line 4—4 of Figure 3.

Figure 5 is a cross-section the plane of which is indicated by the line 5—5 of Figure 3. 35

Figure 6 is a bottom plan of the drill bit shown in Figure 3.

Figure 7 is a cross-section on a diametral plane of a modified form of drill bit in accordance with my invention. 40

Figure 8 is a cross-section the plane of which is indicated by the line 8—8 of Figure 7.

Figure 9 is a cross-section on a diametral plane of a further modified form of drill bit in accordance with my invention. 45

Figure 10 is a cross-section the plane of which is indicated by the line 10—10 of Figure 9.

Figure 11 is, in general, a cross-section on a diametral plane of an additionally modified form 50 of drill bit in accordance with my invention.

Figure 12 is a cross-section the plane of which is indicated by the line 12—12 of Figure 11.

Figure 13 is a cross-section on a diametral plane at right angles to the plane of section of 55

Figure 11, showing the modification of Figure 11 in accordance with my invention.

Figure 14 is a transverse cross-section the plane of which is indicated by the line 14-14 of Figure 13.

In its preferred form, the apparatus of my invention includes a drill adapted to reciprocate and to be supplied with fluid under pressure, to remove, through a suitable channel, the excavated material by means of the fluid lift principle, either alone or in conjunction with liquid jets for assisting in dislodging the material to be excavated and in discharging such material.

The preferred form of the apparatus of my invention and the method of practising the same are utilized in conjunction with material 6 to be excavated, which is of an unconsolidated or somewhat consolidated character and is located at a considerable depth below the surface 7 of a body of water 8. If the water 8 is subterranean, the surface 7 is the ordinary water table. Adjacent the water 8 there is an elevation 9, either natural, such as the ground or a bank, or artificial such as a wharf or pier.

In following my invention, according to one modification I preferably sink a casing 11 of any suitable type and construction and of any desired cross-sectional shape, whether round or non-circular being immaterial. The casing is rested upon the surface of the material 6 and extends upwardly above the level of the water table 7. I preferably fill the interior of the casing to an appropriate height with liquid such as water or muddy water, by any convenient means. In Figure 1 there is diagrammatically represented a pump 12 drawing from a pond 13 and driven by a suitable motor 14 to discharge through a pipe 15 to maintain a water level 16 within the casing. The level 16 may be even with, above, or below the surface 7, but usually is above the level 7, so that there is a differential head or pressure on opposite sides of the casing tending to cause a flow from within the casing outwardly thereof, and of sufficient pressure to assist in maintaining in position the material 6 surrounding the excavation.

The flow of fluid from the interior of the casing generally outward and upward exteriorly of the bottom thereof is sufficient to lubricate the entering portion of the casing where ordinarily the casing would contact the surrounding material. Lubrication by such liquid is especially effective where the casing is forced through material having a tendency to cave, since usually under such circumstances the skin friction is excessive; but by maintaining a flow of water generally upward over the lower portion of the exterior of the casing, such material is maintained away from the surface of the casing and the skin friction is radically reduced. Furthermore, in the event the casing is in cavy or sandy material and it is desired to maintain such material virtually in place and out of the excavation, relatively muddy water, either naturally available or made by adding clay to the available water, can be forced upwardly around the cutting edge and the lower exterior surface of the casing, in order to mud off the surrounding formation and maintain such formation in place against caving or undue contact with the casing itself. By "mud off", I mean to fill under pressure the interstices of porous material with mud or clay to provide a substantially impervious, structurally strong barrier.

In order that the casing may be progressively

lowered into the formation 6, and in order that a suitable excavation can be made, I preferably locate in a suitable place a drill rig, generally designated 17, which in the present instance includes a transporting truck 18 on which a boom 19 is mounted for universal orientation. The boom is provided with the customary controls and is likewise provided with a drill line 21 which is suitably reciprocated by rotating idler 22 and passes over a pulley 23 at the outer end of the boom. Associated with the pulley structure is a guide 24 for a drill stem 26 forming part of a drill structure generally designated 27. The stem 26 is provided with an attachment 28 to which is secured the operating line 21, so that upon rotation of the idler 22 the drill structure is reciprocated in a vertical direction.

At the lower end of the drill structure I provide a drilling bit 29 which is adapted to engage with and cut and excavate the material in the bottom of the casing 11. That is, the up-and-down churning and cutting movement of the bit is effective to dislodge, chop up or cut and break up the material from the surrounding formation. The vertical reciprocation of the bit also produces a lateral surging and turbulence of the water under the bit, which helps to erode and dislodge the material to be excavated. Because of the universal orientation of the boom 19, the drill structure 27 can be moved to any desired location within the casing 11, so that excavation can be carried out at any desired point, close to the casing wall or otherwise, in order to provide a proper hole. The cutting function of the drill bit is especially valuable in piercing a stratum of clay to a sand stratum beneath. Excavation of the underlying sand facilitates the caving and collapse of the clay layer and thus expedites its removal. It is thus feasible to operate with casings which are not circular in cross-section, and particularly is the maneuverability of the drill valuable in the event the cutting edge of the casing should strike a boulder or other impediment, in which instance the drill can excavate the material from beneath the boulder, permitting it to fall inwardly out of the way of the cutting edge.

In order to remove from the excavation the material which is excavated by the drill bit 29, and in order to maintain such removal inexpensively and at a rapid rate, I preferably provide a duct 32 leading from a suitable source of fluid under pressure, such as air or steam, and connecting through a suitable flexible connection 33 with a conduit 34 running parallel with the drill structure 27, and, particularly as shown in Figure 3, at a convenient point above the drill bit 29 connecting by means of a fitting 36 with an annular chamber 37 within the drill body 38 and in part defined by a discharge conduit 41. Fluid such as air under pressure which is conducted through the connected conduits is discharged into the annular space 37, from whence discharge takes place through a plurality of apertures 42 which preferably pierce the wall of the discharge pipe 41 at an inclination not only to the horizontal but likewise to the axis of the discharge pipe, so that the air jets thereby formed produce a swirling motion within the discharge pipe 41. The churning movement of the drill structure maintains the discharging material in an agitated and fluid condition.

The pipe 41 communicates with a plurality of slots 43 in the drill bit, the slots being disposed preferably between radial fins 44 projecting from the main body of the drill bit. Thus, as the drill

churns into the formation, portions thereof pass upwardly through the slots 43, particularly as the drill descends, and are caught up in an upwardly moving current of liquid and air mixed and thus, 5 by means of the air lift, are carried upwardly through the discharge pipe 41, not only by virtue of the air present therein but likewise due to the hydrostatic pressure thereon, and are discharged from the structure through an elbow 46 terminating 10 in a length of flexible hose 47 which discharges in a dump 48. The mixture of liquid and excavated material discharged at the dump separates into a pile of excavated material and water, which latter returns to the pond 13 for re-use if desired. Addition of suitable material either from the dump 48 or otherwise, to the water in the pond 13, can be resorted to, if necessary, for mudding off. There is therefore provided, in accordance 15 with my invention, an apparatus for excavating the material at the bottom of a casing, the extraneous, non-excavated material being maintained in place by high aqueous pressure and/or mudding off, and means for removing the excavated material by means of the fluid lift mechanism to a suitable point of discharge.

In the operation of this structure, the excavating action is carried on until it is necessary to add additional length of drill structure and additional length of casing, both of which are done 20 in the customary fashion for these jointed structures. In the event the formation is sand or sandy material, there is little difficulty in continuing indefinitely with the excavation, but in the event boulders or large rocks are encountered 25 which cannot be broken by the churning of the drill bit, I preferably let such boulders and rocks accumulate at the bottom of the excavation; then, when there are sufficient to justify the action, the drill structure is withdrawn or moved aside and 30 an orange-peel or clam-shell bucket is lowered into the casing to remove the accumulated rocks and boulders, after which the drill resumes its excavating action as heretofore described.

In many cases excavation is carried on without 35 the use of casings. As one of the many examples of such work, there is illustrated in Figure 2 a scheme especially useful in recovering valuable material such as gold-bearing gravel. In this environment the ground level is generally designated 40 6' and overlies bed rock 7' above which is situated the material 8' to be excavated. The normal water table 9' is considerably below the ground level 6'. In carrying out my invention I utilize a barge 11' floating on a natural or 45 artificial body 12' of water, which, in the latter case, can be supplied from a well pump 10' extending to the water table 9'. Since the apparatus of my invention is capable of excavating to a considerable depth, and since the ordinary dredge is limited in working depth, it is often expedient to 50 mount my apparatus on the rear of a dredge which is represented by the barge 11'.

The apparatus includes a drill boom 13' carrying 55 a drill structure 14' which is suitably reciprocated. The drill structure includes a drill bit 16', of a type similar to that illustrated in Figure 1, which is supplied with air or other fluid under pressure through a line 17' extending from a suitable source. The churning and cutting 60 action of the drill bit dislodges the material to be excavated, in this case the material 8', which is conducted through the drill structure 14' to a suitable point of discharge by the fluid or air lift described in detail in connection with Figure 75 1. If required, some of the excavated material, or

even suitable material from another source, can be used to mud off the walls of the pond 12' in order to maintain therein a water level higher than the water table 9'.

In certain types of formation, particularly in 5 clay material, I have found that the progress of excavation can be accelerated by the use of a jet of fluid such as steam, water or muddy water in addition to the fluid or air lift. Under such circumstances, I preferably provide the drill 10 structure with a conduit 51 for conducting such liquid, which conduit connects by a fitting 52 with a pipe 53 passing through the annular space 37 and discharging into an annular space 54 which is isolated from the remainder of the drill 15 body by annular barriers 56 and 57. The barrier 57 is preferably formed integrally with the drill bit and is pierced by a plurality of ducts 58 each of which terminates in a discharge orifice 59 adjacent one of the drilling fins or webs 44 and 20 is inclined in a suitable direction to assist in washing loose the material to be excavated. The orifices 59 can be supplied with fluid intermittently or continuously, depending upon the operating conditions.

Under certain conditions of operation, and 25 particularly with certain formations, I have found it feasible to dispense with the use of compressed air as a lifting medium. Under such circumstances, I preferably use a drill bit substantially as shown in Figures 7 and 8. In this instance, the outer casing 71 surrounds a discharge pipe 72. Fastened to both of these pipes is a drill head 73 incorporating a plurality of 30 cutting fins 74. Communication from the exterior to the discharge pipe 72 is established by means of a plurality of apertures 76 preferably located intermediate the fins 74. In order to facilitate the discharge of material which is removed by the drill, I provide a jet of liquid such 35 as water, or water and mud. To this end a conduit 77, leading from any suitable source, extends between the outer jacket 71 and the inner pipe 72 and terminates in an annular barrier or ring 78. Communicating with the conduit 77 is an annular chamber 79 which in turn leads into a plurality of passages 81 piercing the material of the drill head. These passages preferably unite in a horizontal duct 82 in the lower portion of the drill head and in turn communicate with a suitable nozzle 83 which is disposed 40 axially of the drill bit and is adapted to discharge upwardly into a diverging diffusing chamber 84. The velocity of efflux of the material from the nozzle 83 is effective to establish a vacuum to 45 induce flow of excavated material and liquid through the aperture 76 and to impel such material upwardly in the discharge pipe 72 to be released from the mechanism at any appropriate point.

Under certain other conditions of operation, particularly in rather heavy clay, I have found it advisable to provide a drill bit substantially as shown in Figures 9 and 10. In this instance, the drill head 81 is connected to an outer shell 82 50 and to an inner shell 83, as before. Between the shells is disposed a liquid conduit 84 which leads into an annular chamber 86 defined by a barrier 87 and by the upper terminus of the drill body 81. Communicating with this annular chamber 55 is a plurality of passages 88 which pass through the drill body and merge into a common chamber 89. Situated on a nipple 90 communicating with the chamber 88 is a nozzle 91 pierced by a plurality of jet orifices 92 each of which is di- 70 75

rected generally upwardly and outwardly and, in fact, in line with the inlet apertures or slots 93 which pierce the body of the drill. The direction of the apertures 92 is such that when the 5 drill body is in a rather clayey formation the upward jets tend to cut under the clayey material and dislodge it for discharge in the pipe 83 and can be directed to jet under the cutting shoe 10 of a casing to reduce skin friction. Since the 10 direction of the jets is upward, material such as clay is broken off upwardly. This action is very effective, due to the absence of backing or support above the clay, in distinction to jetting 15 downwardly into a solid, well supported clay mass.

For certain other uses, particularly where it is desired to excavate along a generally horizontal plane, especially in excavating value-bearing gravel adjacent the bottom of a dredge operation, such, for instance, as shown in Figure 2, I 20 preferably provide my apparatus with a drill bit substantially as shown in Figures 11 to 14 inclusive. In this instance, the drill head 101 is of generally cylindrical shape with a relatively flat 25 bottom. It likewise is provided with a plurality of axially disposed, radially-extending fins 102. The interior of the body is contoured to provide a passage 104 communicating with a suitable discharge pipe and is preferably upwardly flared 30 to provide a conical diffusing chamber 106. Discharging into the chamber 106 is a liquid nozzle 107 which communicates by means of a transverse passage 108 with a plurality of supply passages 109 connected to a source of liquid under 35 pressure, as hereinabove indicated. Intersecting the conical diffusing chamber 106 is a plurality of ducts 111 which, instead of emerging from the sides of the drill body, emerge therefrom in the bottom portion, so that in use the entrance 40 to the passages or ducts 111 is as close as possible to a horizontal layer of material to be excavated. In the operation of this form of the structure, liquid discharging from the nozzle induces flow 45 inwardly through the ducts 111 and is effective to excavate material, during the operation of the drill bit, from substantially a horizontal plane.

I claim:

1. A method of excavating comprising establishing a desired liquid level above the material 50 to be excavated, dislodging and preparing said material at least partially by upwardly directed liquid jets, mixing the prepared material with a carrier fluid, and driving the mixture by fluid pressure upward through but isolated from said liquid to a point of discharge.

2. A method of excavating in material including an upper, clay stratum and a lower, sand stratum, comprising establishing a desired liquid level above said material, dislodging and 55 penetrating said clay stratum by successive impacts thereon, mixing said dislodged clay material with a carrier fluid, driving said clay mixture by fluid pressure upward through but isolated from said liquid to a point of discharge, and continuing to dislodge and preparing said sand stratum, mixing said dislodged sand material with a carrier fluid, driving said sand mixture by fluid pressure upward through but isolated from said liquid to a point of discharge, and continuing to dislodge and discharge said sand until said clay is undermined and settles.

3. A method of excavating easily dislodged material comprising, establishing a desired liquid level above the material to be excavated, suspending a dislodging, churning and discharging as-

sembly above the same, causing the assembly to fall successively upon and into the dislodged material, thereby breaking up and churning the same, mixing the churned material with a carrier fluid outside the assembly, moving the mixture by suction into the assembly, further mixing and agitating material and carrier fluid within the assembly, moving the mixture into a discharge conduit surrounded by liquid to a desired level, driving the mixture by fluid pressure upward and out of the discharge conduit, moving the assembly from one desired location to another in any direction within the excavation, holding the same in any location for a controlled period of time, and forcing the assembly into co-operative relationship with undisturbed material to be excavated, to dislodge the same.

4. Claim 3, and replacing with added liquid the liquid removed from the space just outside the assembly.

5. Claim 3, in which additional fluid is added to the mixture within the assembly.

6. Claim 3, in which a whirling motion in the discharge conduit is caused by the introduction of the added fluid.

7. Claim 3, and driving into the assembly, by the force of the impacts, a part of the material to be excavated.

8. Claim 3, in which a turbulence is created, due to the form of the assembly, between the assembly and the undisturbed material.

9. Claim 3, in which operations on the material are facilitated by the use of jets.

10. Claim 3, in which a portion of the discharge is returned to the excavation.

11. Claim 3, in which said suction is induced by lightening the column in the discharge conduit.

12. Claim 3, in which the final upward movement of the mixture is induced by lightening the column within the discharge conduit.

13. A method of excavating comprising, directing a jet of liquid against the material to be excavated, to dislodge the same, the direction of said jet being fixed above the horizontal so as to attack the material from below, giving it a cavity to break to on two sides, moving the jet about on the face of the undisturbed material, fixing the position of the jet with respect to the face at any point for a controlled period of time, dislodging the attacked material and removing the same.

14. Claim 13, and removing said material by suction.

15. Claim 13, in which the dislodged material is further disintegrated and mixed with a carrier fluid before being removed from the excavation.

16. Claim 13, in which the removal means is kept from clogging by jet action.

17. Claim 13 in which the dislodged material is removed through a removal assembly with an intake, and in which the jets perform the double function of keeping the removal assembly free from clogging at the intake, and at the same time attacking the material to be excavated.

18. An excavating apparatus comprising, in assembly, a reciprocating hollow bit and drill stem combination, means for reciprocating the same, means to reduce fluid pressure within the assembly, a conduit to conduct fluid downward to the lower part of the assembly, means to dislodge and agitate the material to be excavated, means to mix the same with a carrier fluid outside the assembly, means to bring said mixture

within control of the assembly, means to further mix material and carrier fluid within the assembly, another upwardly extending discharge conduit, means to cause the mixture to move into the same, means to cause an upward flow in said discharge conduit, means to discharge the mixture upward and from said conduit, means to hold the assembly in a positively controlled desired operating position, means to move the assembly from place to place within the excavation, in any direction, all in co-operative relationship, and means to operate the entire apparatus.

19. Claim 18, in which the drill stem is hollow and is designed as the upward or discharge conduit.

20. Claim 18, and means to direct the descending fluid into the discharge conduit at an angle upward to the axis thereof.

21. Claim 18, in which apertures are provided in the wall of the bit for the entrance of material thereinto.

22. Claim 18, in which cutting fins are attached to the bit.

23. Claim 18, in which the body of the bit is conical or wedge shaped at its impacting end. 10

24. Claim 18, and means to introduce a liquid and means to introduce a gas into the carrier fluid within the assembly.

LEO RANNEY. 15
